[57] CLAIM

The ornamental design for a can or the like, as shown and described.

DESCRIPTION

FIG. 1 is a perspective view of a can or the like showing my new design.

FIG. 2 is a front elevation view.

FIG. 3 is a side elevation view.

FIG. 4 is a top plan view.

FIG. 5 is a bottom plan view.

The rear of the can and the side not shown are the same in appearance as the front and side shown in FIGS. 2 and 3, respectively.

FIG. 1

FIG. 2

FIG. 3

FIG. 4

FIG. 5
